INHALANT

Frank O. Taylor and Harvey M. Merker, Detroit,
Mich., assignor to Parke, Davis & Company,
Detroit, Mich., a corporation of Michigan

No Drawing. Application November 16, 1936,
Serial No. 111,174

6 Claims. (Cl. 167—58)

This invention relates to therapeutic agents of that type which are useful for the treatment of the nose and throat and are commonly referred to as inhalants.

- 5 One of the objects of the invention is to obtain an improved therapeutic agent of the above mentioned type which is more readily absorbed and consequently more rapid in its therapeutic effect.
- 10 Another object is to provide an improved inhalant which is relatively non-irritating when applied to the mucous membranes.

Another object is to produce a therapeutic agent effective as a vasoconstrictor, pleasant in effect and of such a character as to inhibit all bacterial and fungus growth.

In the broader aspects of our invention the new therapeutic agent comprises an aqueous solution of a glucose base, a vasoconstrictive substance and sufficient preservative to inhibit any bacterial or fungus growth in the glucose base. The vasoconstrictive substance may be ephedrin, epinephrin or other natural or synthetic substance having similar properties. Chlorthymol is 25 another substance which in some cases may be used in the invention. The vasoconstrictor may be used in any form in which it is soluble in water, preferably in the form of salts such as the chloride, sulphate, lactate and other equivalents. It 30 is preferably used in amounts to give a solution of not over 5% of the alkaloid, and in general a satisfactory amount is the equivalent to a 1% solution of the same.

The glucose base is preferably dextrose since 35 it may be obtained in a very pure form. The solution should preferably contain at least 2½% dextrose, and 5% is a desirable quantity although more may be used in some cases. In general the solution contains dextrose in sufficient quantities 40 to make it approximately isotonic or in some cases hypertonic. The preservative used must be one having antiseptic properties sufficient to inhibit all bacterial and fungus growth and at the same time not having irritating properties 45 when applied to the mucous membranes. A satisfactory chemical for this purpose is chlorbutanol.

An example of a therapeutic agent of our invention is one having the following composition:

Ephedrin lactate equivalent to 1% of ephedrin.
Dextrose 5%.
Chlorbutanol 0.5%.
Menthol 0.1%.
55 Water.

The above compound may be rendered still more suitable for therapeutic use by incorporating a small amount of perfume oils, such as oil of lavender, and an anilin dye. A small amount of alcohol is used to render the oils soluble. The 5 amount is restricted to avoid irritation. 2% alcohol is sufficient to dissolve the oils and does not cause irritation.

Instead of ephedrin lactate in the above formula, any other salt of ephedrin may be used such 10 as ephedrin chloride, sulphate, etc. The corresponding salts of epinephrin may also be substituted, and if desired the ephedrin and epinephrin may be used in combination.

Chlorbutanol may be used up to the limit of 15 its solubility, but preferably five-tenths of 1% is used since this is sufficient for the purpose. Instead of using chlorbutanol in the above formula, other germicidal and fungicidal agents may be used providing they are non-irritating. 20 Examples of other compounds are phenyl mercuric lactate, phenyl mercuric glycolate, phenyl mercuric tartrate and other phenyl mercuric salts of an aliphatic hydroxy carboxylic acid.

A therapeutic agent of the invention as above 25 described may be used as a spray or as drops and is of particular utility for the treatment of the nose and throat. It is less irritating than previously known aqueous or oil solutions of ephedrin, epinephrin and other vasoconstrictive 30 agents.

What we claim as our invention is:

1. A therapeutic agent in the form of an inhalant for local application comprising an aqueous solution of a vasoconstrictive substance, 35 dextrose in amount not substantially less than that sufficient to make an isotonic solution and a germicidal agent in amount sufficient to inhibit bacterial and fungus growth in the solution.

2. A therapeutic agent in the form of an inhalant for local application comprising an aqueous solution of a vasoconstrictive substance, dextrose not less than 2½% and a germicidal 40 agent in amount sufficient to inhibit bacterial and fungus growth in the solution.

3. A therapeutic agent in the form of an inhalant for local application comprising an aqueous solution of an ephedrin compound, dextrose in amount not substantially less than that sufficient to make a substantially isotonic solution and chlorbutanol in amount sufficient to inhibit bacterial and fungus growth in the solution. 45

4. A therapeutic agent in the form of an inhalant for local application comprising water, 55

ephedrin lactate equivalent to 1% of ephedrin, dextrose 5%, chlorbutanol 0.5% and menthol 0.1%.

5 5. A therapeutic agent in the form of an inhalant for local application comprising an aqueous solution of ephedrin lactate, dextrose in amount not substantially less than sufficient to make an isotonic solution, and a germicidal agent in amount sufficient to inhibit bacterial and fungus growth in the solution.

6. A therapeutic agent in the form of an inhalant for local application comprising an aqueous solution of ephedrin lactate, and dextrose in amount not substantially less than that required to make an isotonic solution.

5
